UNITED STATES PATENT OFFICE.

FREDERICK A. DIESTELKAMP, OF BLAND, MISSOURI.

AUTOMATIC MAGAZINE FIREARM.

1,126,726.

Specification of Letters Patent.

Patented Feb. 2, 1915.

Application filed October 6, 1913. Serial No. 793,618.

To all whom it may concern:

Be it known that I, FREDERICK A. DIESTELKAMP, citizen of the United States, residing at Bland, in the county of Gasconade and State of Missouri, have invented certain new and useful Improvements in Automatic Magazine Firearms, of which the following is a specification.

My invention relates to firearms and particularly to automatic firearms.

The primary object of my invention is the provision of a magazine firearm wherein positive means shall be provided for shifting the magazine follower upward to feed the cartridges one by one into the receiver.

A further object of the invention in this connection is to provide means whereby to indicate to the user the number of cartridges remaining in the magazine.

20 A further object of the invention is to provide means actuated upon the explosion of a cartridge in the firing chamber for locking the trigger from any tripping movement.

25 A further object of the invention is the provision of means whereby the breech block may be drawn back by hand to cock the hammer in case of a misfire or to return the parts to firing position and operate the rifle.

30 A further object of the invention is to provide a firearm having a magazine and a follower with a flexible follower operating band or chain, and to provide means for taking up this band a predetermined distance upon each discharge of the gun to thereby cause the follower to move upward within the magazine chamber and positively feed a cartridge into the receiver.

35 A further object in this connection is to provide a spring acting to return the follower actuating band to its normal position and to provide means for releasing the flexible band or chain after the last cartridge has been fed into the breech to permit the 45 return of the follower to its normal position and to permit the magazine to be filled again with cartridges.

Still another object is to provide means whereby the breech block may be locked in 50 its retracted position after the firing of the last cartridge and whereby the magazine loading door or lid may be automatically opened at this time.

Still another object is to provide manu-

ally operated means for opening the door of the magazine when desired.

A still further object, and one of the main objects, is to provide a breech block that will lock behind the barrel and so give the projectile time to clear the barrel while the block is unlocking, and while the barrel remains perfectly stationary.

My invention is illustrated in the accompanying drawings, wherein:

Figure 1 is a perspective view of a firearm 65 constructed in accordance with my invention; Fig. 2 is an enlarged vertical section through the firearm, this section being taken on the line 2—2 of Fig. 4; Fig. 3 is a section on the line 3—3 of Fig. 2; Fig. 4 is a section 70 on the line 4—4 of Fig. 2; Fig. 5 is a longitudinal section on the line 5—5 of Fig. 2; Fig. 6 is a section on the line 6—6 of Fig. 2; Fig. 7 is a perspective view of the mechanism for operating the loading door; Fig. 8 75 is a perspective view of the mechanism for operating the loading door and for locking the trigger; Fig. 9 is a perspective view of the cartridge feeding wheels or rollers; Fig. 10 is a perspective view of the breech bolt 80 and of the firing pin separated therefrom; Fig. 11 is a perspective view of the breech block and the mechanism for manually retracting it; and Fig. 12 is a section on the line 12—12 of Fig. 2. Fig. 13 is a perspective 85 view of the pawl release mechanism.

Corresponding and like parts are referred to in the following description and indicated in all the views of the accompanying drawings by the same reference characters.

Referring to Fig. 1 it will be seen that my improved gun comprises a barrel 2, a receiver 3, a forearm 4 and a stock 5. The barrel 2 is screw threaded into the forward end of the receiver as clearly shown in Fig. 95 2 and the rear end of the forearm is inserted within a socket in the receiver, the forward end being held to the barrel in any suitable manner. The stock is held to the receiver by means of upper and lower tangs. 100 The receiver is hollow to contain the firing and cartridge feeding mechanism, and forming part of the receiver is the magazine 6, in which the cartridges *a* are disposed one on top of the other. As will be seen in Fig. 105 4, the lower portion of the receiver is divided into two parts by means of a vertical wall 7, the cartridges *a* being contained

within the magazine chamber 6 formed between the wall 7 and one of the outer walls 8 of the receiver.

Disposed within the upper portion of the receiver and normally immediately behind and abutting against the rear end of the barrel 2, is a cylindrical hollow breech block 9, and disposed within the interior of this breech block 9 and normally projecting therefrom is a piston constituting a breech bolt and designated 10. This piston has the shape illustrated in Fig. 10. The forward portion of the breech bolt 10 has a diameter equal to that of the cartridge chamber 11 formed by the rear portion of the bore of the barrel. The rear portion of the breech bolt is reduced in diameter so as to pass through a perforation 12 formed in the rear end of the breech block, 15 while adjacent its head the breech bolt is enlarged as at 13 and formed with relatively heavy screw threads which coact with relatively heavy screw threads 14 formed in the interior of the forward portion of the breech block. A spring 15 surrounds the rear portion of the breech bolt and is disposed between the perforated end of the cylindrical breech block 9 and the head 13 so that normally the breech bolt is forced forward so as to abut against the cartridge *a* in the manner shown in Fig. 2. The forward end of the breech bolt is formed with resilient hooks 16 adapted to engage over the rim of a cartridge as illustrated clearly in Fig. 30. The breech bolt is tubular, and disposed within the breech bolt is the firing pin 17 which projects out through the rear end of the breech bolt and is formed with a head 18. Disposed between this head 18 and the head 19 formed on the rear end of the breech bolt is a spring 20 which urges the firing pin rearward but permits the firing pin to be forced forward and impinge upon a cartridge to discharge the latter. 45 The forward end of the cylindrical breech block 9 as illustrated clearly in Fig. 11 is provided with a plurality of radially directed locking lugs 21. There are four of these lugs illustrated, shown as arranged in quartering relation. The forward end of the receiver just rearward of its point of attachment to the barrel is also provided on its interior with four radially projecting, inwardly extending locking lugs 22 shown clearly in Fig. 4. Normally the lugs 21 are disposed in registry with the lugs 22 and prevent any rearward movement of the breech block. When, however, the breech bolt or piston 10 is forced rearward by the 50 firing of a cartridge, the screw threads 13 engage the screw threads 14 and this causes a rotation of the breech block through an eighth of a revolution until the lugs 21 escape from registry with the lugs 22, whereupon the cylindrical breech block will move.

rearward together with the breech bolt in a manner to be hereafter and more specifically stated.

For the purpose of preventing any rotation of the breech bolt 10, I provide the head 19 with laterally extending wings 23 as shown clearly in Figs. 5 and 10, these wings engaging in guide grooves 24 extending longitudinally of the receiver, and for the purpose of urging the breech bolt 75 and the breech block forward, I provide the springs 25 disposed one on each side of the receiver and surrounding the guide rods 26 which pass through perforations in the wings 23. These guide rods 26 extend 80 through the rear end of the receiver and are held rigidly in position in any suitable manner and the springs 25 surround these guide rods and bear against the wings 23 so that any rearward movement of the breech block 85 and the breech bolt causes a compression of these springs 25 and when the momentum of the rearward moving breech block and breech bolt has been sufficiently reduced, the springs 25 will act to return the parts to 90 their initial position.

Mounted within the receiver at the rear end thereof and extending upward and forward therein, and projecting at its rear end partially into the stock, is the hammer 27. 95 This consists of a straight rod as shown in Fig. 8 which impinges against the downwardly and forwardly beveled face of the head 18 and which is surrounded by a coil spring 28 bearing at one end against the 100 flanged end of a sleeve 29 and at its other end against a collar 30 formed upon the hammer. This collar as illustrated in Fig. 8 is provided with the downwardly and forwardly projecting lug or tooth 31 for engagement with a sear as will be later stated. The trigger is mounted within the trigger plate 32 which forms part of the receiver, though it may be a separate piece. This trigger plate is slotted at 33 for the downward prolongation or finger piece 34 of the trigger 35. The trigger 35 is pivoted upon a pivot pin 36 mounted in bearings on the trigger plate. As shown in Fig. 8, the trigger has a rearward extension 39, to which 110 is pivoted an upward and rearwardly extending link 40. This link at its upper end is pivotally connected to a sear 41 in turn rotatably mounted upon a bracket 42 mounted within the receiver. This bracket 42 extends upward so as to support the sear 41 adjacent to the line of travel of the tooth 31 on collar 30. The forward end of the sear is formed with a hook 43 adapted to engage over the tooth 31 as illustrated 115 clearly in Fig. 8. A spring 44 tends to force the rear end of the trigger downward and this, of course, will force the forward end of the sear upward. The forward end of this sear forward of the hook 43 is rounded or 120 125 130

beveled. The trigger is also formed with a forward prolongation 45 whose lower face is slightly elevated above the pivotal center of the trigger for a purpose which will be later described.

Upon the recoil of the breech block and breech bolt under the explosion of a cartridge, the breech bolt and block will move rearward, and in doing so will force the hammer downward and rearward against the force of the spring 28. This downward and rearward movement of the hammer will continue until the breech block and bolt have nearly reached the ends of the grooves 24, and at this point the hammer will escape from its engagement with the head 18 of the firing pin and from its engagement with the rear end of the breech block and breech bolt, and at this point the tooth 31 will slip into engagement with the hook 43 and the parts will assume the position shown in Fig. 2. The hammer is then cocked and it will be obvious that upon a pull being given to the trigger, the forward end of the sear will be depressed, thus releasing the hammer. The hammer will spring forward under the impetus of the spring 28 and impinging upon the firing pin will force the firing pin forward to explode the cartridge. As soon as the pressure of the finger upon the trigger has been released, the spring 44 will act to return the trigger to its normal position with the hook 43 in the path of movement of the tooth 31. I also provide means whereby the hammer can be cocked by hand in case of misfire but this will be later described.

The mechanism for feeding cartridges from the magazine 6 consists of a follower 46 normally disposed, when the magazine is full, at the lower end of the magazine but movable upwardly between the walls 7 and 8 to feed the cartridges one by one into the receiver. Disposed forward of the magazine in a chamber 47 is a shaft 48 and surrounding the shaft is a convolute spring 49 which is operatively connected to one end of a flexible chain or band 50. This chain passes from the compartment 47 beneath a roller 51 mounted upon the lower end of the magazine wall, then extends rearwardly beneath the magazine and beneath the follower 46 and passes under a roller 52 mounted upon the lower end of the rear magazine wall. The flexible connection then extends upward parallel to the rear wall of the magazine and over a roller 53 mounted upon the upper end of this rear wall. The flexible connection is connected to the follower by means of an inwardly extending screw or pin 54 and a guide block 55 which is attached to one end of the follower. This guide block moves in guide grooves 56 formed in the opposite walls of a slot 57 which extends upward through the rear wall of the magazine. It

will be obvious now that by drawing the flexible connection rearward, the slide or block 55 will be raised and this will cause the follower to be raised and elevate the cartridges a.

For the purpose of automatically winding up the flexible connection 50 and thereby raising the follower 46 I provide the winding wheel 58 illustrated in detail in Fig. 9. This winding wheel, roller or drum 58 is mounted upon a shaft 59 which is rotatably mounted in suitable bearings formed in the receiver, this shaft also carrying upon it the toothed wheel 60 as illustrated in Fig. 9. At one point in its circumference the winding roller or drum 58 is formed with an upwardly projecting lug 61 through which passes a rod 62 which is operatively connected to the rear end of the flexible connection 50, preferably by means of a spring 63, there being a nut on the end of the rod whereby the tension of the spring may be regulated. The wheel or roller 58 is also provided with the radially extending stop lug 64 which when the magazine is full bears against a stop shoulder 65 projecting from the wall of the receiver. As illustrated, the wheel 58 upon its left hand face is provided with a plurality of numerals disposed equidistantly and running as illustrated from 1 to 8, it being of course understood, however, that there may be a greater number of these numerals or less depending upon the number of cartridges held in the magazine. As illustrated, there are seven cartridges in the magazine and one in the barrel and eight numerals, the numeral 1 being located adjacent to the lug 61. The side wall of the receiver is formed with a perforation 3a, (seen in Fig. 1) through which these numerals may be read, this perforation being so located that when the magazine is full and has, for instance, seven cartridges therein, the numeral 8 will show, while when the magazine has only one cartridge therein, the numeral 2 will be displayed. For the purpose of shifting the wheel 58 a predetermined distance upon each opening of the breech, I pivotally mount upon the breech block 9 the downwardly and rearwardly extending pawl 65 as seen clearly in Fig. 2. This pawl is held in its engaging position by means of a spring 66. Upon a sufficient rearward movement of the breech block 9 to fully open the breech, the pawl 65 engages with one of the teeth 60a upon the wheel 60 and this engagement will of course cause the wheel 60 to rotate, rotating the shaft 59 and the wheel 58 a distance sufficient to wind up a certain length of the flexible connection 50 and so force a cartridge into the receiver. Upon a return movement of the breech block, the pawl 65 will, of course, yield and escape the teeth 60a. The wheel 60 is held from any reverse 130

rotation by means of a hook-shaped pawl 67 pivotally mounted upon a pivot pin 68 extending from the wall of the receiver, the upper end of the pawl being hook-shaped to engage over the teeth 60^a. The upper end of the pawl is yieldingly forced inward by means of a spring 69 surrounding the pin 70 bearing against the pawl as shown in Fig. 2. The lower end of the pawl is formed 10 with a forwardly and laterally projecting arm 71 (see Fig. 7).

The ejecting mechanism whereby the empty shell is ejected from the receiver is illustrated most clearly in Fig. 2 and is also 15 illustrated in Fig. 4. As will be seen from Fig. 4, the receiver is divided into two compartments by the vertical wall 7, one of these compartments forming the magazine while the other compartment 7^a forms an 20 ejecting chamber. Mounted upon the upper end of the wall 7 is a magazine gate 72 which is normally held over the uppermost cartridge. When the uppermost cartridge is discharged into the receiver this door 72 will 25 open, but immediately upon the passage of the cartridge into the receiver the door will swing back into the position shown in Fig. 4. Pivotally mounted upon the upper wall of the receiver is a bell crank lever 73 having 30 a long arm and a short arm. The long arm normally extends forward and is designated 74 while the short arm extends normally downward and is connected to a rod 75 which extends rearward and in turn is 35 connected to a lever 76 forming a finger. This lever is pivoted as at 77 to the upper wall of the receiver, and a spring 78 resiliently urges the lower end of the finger forward. This finger is disposed in the path 40 of movement of the breech block 9 so that when this breech block is forced back by the recoil of the discharging cartridge, it will contact with the lower end of the finger 76, shift it rearward, pull rearward upon the 45 rod 75 and throw the long arm of the bell crank lever 74 downward into the receiver and against the exploded shell held upon the breech bolt 10 by the spring clip 16. The long arm 74 of this ejector lever will, therefore, 50 force the empty shell out of its engagement with the spring clip 16 and cause this shell to drop into the ejecting chamber 7^a and be discharged from the lower end thereof onto the ground. It will be noted 55 that the shell is not discharged laterally so that it will fly in all directions but that it falls directly downward. Immediately upon the forward movement of the breech block from its rearward position, the spring 78 60 will act to return the parts of the ejecting mechanism to their normal position shown in Fig. 2.

For the purpose of holding the door 72 yieldingly closed and for the purpose of

locking the trigger, I provide the mechanism 65 illustrated in Fig. 8. The door 72 it will be seen is mounted upon a rock shaft 79 having a crank arm 80 at one end. This rock shaft is mounted in suitable bearings in the forward and rear walls of the magazine. 70 The extremity of the crank arm 80 is connected to a spring 81 which in turn is connected to a bracket 82. Passing upward through this bracket 82 is a rod 83 normally forced upward by a spring 84 bearing 75 against a collar 85 on the rod. This rod as illustrated in Fig. 6 is so disposed in the receiver that its upper end is normally in contact with one of the lugs 21 on the breech block, and when the breech block is rotated 80 in the direction of the arrow, Fig. 6, it will release the rod 83 and permit it to be forced up by a spring 84. The lower end of the rod 83 is connected to one arm of a bell crank 86, the other arm of which is pivotally connected to a rod 87 which extends rearward through the receiver. The rear end of this rod is disposed adjacent to the forward end of the extension 45 of the trigger 35. When the trigger is released after firing, this forward extension 45 will rise and at the moment that the breech block begins to rotate the rod 87 will be forced rearward by the mechanism heretofore described and the rod 87 will be inserted between the lower face 95 of the extension 45 and the trigger plate, thus locking the trigger in its forward position and preventing any rearward movement of the trigger under pull. I also provide as means for locking the trigger, an 100 angular cam lug or lock 88, shown in Fig. 2, which is pivoted upon the trigger plate at 89. The downwardly extending arm of this member projects below the trigger plate into position to permit the member to be rotated 105 upon its pivot 89 so as to bring the cam portion thereof to bear against the under face 45 of the trigger and move it upward and hold it in this position. A spring 90 acts to hold this locking cam from any accidental 110 movement.

It will be noted that as the cartridges are ejected one by one from the magazine into the receiver, the indicating wheel 58 will turn step by step and the follower will rise 115 until it arrives at the upper end of the magazine and the last cartridge has been forced into the receiver. In order to provide means for automatically returning the follower to its original position immediately after the 120 last cartridge has been discharged, I provide mechanism for releasing the pawl 67 from its engagement with the wheel 60 and also locking the breech block and bolt in their retracted positions until the magazine has 125 been refilled and a new cartridge inserted in the open breech. To this end, I pivotally mount in the lower portion of the receiver

the lever 91, as shown clearly in Figs. 2 and 7. This lever 91 is laterally offset toward its forward end, and is provided with the upwardly and forwardly extending arm 92 formed with a hump 92^a at its middle, and with an upward extension 92^b extending forward at only a slight inclination. This arm is disposed in the path of movement of the lug 64 so that when the wheel 58 has moved 5 the lug 64 into engagement with the arm 92, the forward end of the lever will be depressed and the rear end raised. Pivoted to the rear end of the lever is an upwardly extending rod 94, and projecting laterally from this rod is a lug 95 which engages with the forwardly and laterally projecting arm 71 of the pawl 67. When the rear end of the lever 91 rises by reason of a depression of the forward end of the lever, this lug 95 10 will shift the pawl 67 out of engagement with the teeth 60^a so as to permit a reverse or unwinding movement of the shaft 59 and of the wheels 60 and 58 under the action of the spring 49. The rod 94 is also formed 15 with a forwardly and laterally projecting arm 96 whose forward end is adapted to engage beneath the pawl 65 when the breech block has been shifted to its rearward position, thus leaving the pawl free from the 20 teeth 60^a. The rear end of the breech block is formed with the perforation 97 which registers with the upper end of the rod 94 when the breech block is in its rearmost position and thus when the breech block shifts 25 to its rearmost position under the discharge of a cartridge, and the forward end of the lever 91 has been depressed by the engagement of the finger 92 with the lug 64, the upper end of the rod 94 which constitutes 30 a bolt will be shifted into this perforation 97 and lock the breech block in its rearward position. At the same time that the forward end of the lever 91 is depressed by engagement with the lug 64, the loading 35 door 98 which is disposed in the side of the magazine is automatically opened so as to permit the introduction of new cartridges. This door is actuated by the following mechanism: The door 98 is mounted upon a rock 40 shaft 99 having a crank arm 100. Pivotedly connected to the forward end of the lever 91 is a link 101, the lower end of which is bent to an acute angle, as at 102, and pivoted at 103 to the crank arm 100. When the forward end of the lever 91 is depressed, the 45 arm 100 will be depressed and the loading door will be fully opened. When the loading door is fully opened, the crank arm will move past its center, and the door will be held open with the extension 102 of the 50 crank arm projecting outward.

In order that the loading door 98 may be opened without the necessity of waiting for the last cartridge to be fired, I provide the 55 mechanism illustrated in Fig. 7, this mechanism also locking the forward end of the lever 91 from any accidental depression. Upon a shaft 105 is mounted an arm 106 having spaced laterally extending fingers 107 and 108. The finger 107 extends over 60 the top of the arm 92, while the finger 108 extends beneath the arm 92. The finger 107 carries a knob 109 which projects out through an opening in the receiver in convenient position to be manipulated by the 65 thumb of the operator. It will thus be seen that upon shifting the knob 109 in one direction, the forward end of the lever 91 will be depressed, thus causing a partial opening of the door 98, after which the door may be 70 fully lifted by hand. Usually the forward end of lever 91 is held raised by spring 110. Arm 106 is also held in position to urge the lever 91 upward by a spring 111. The lug 75 64 is angular to provide a shoulder 64^a and 80 a shoulder 64^b. Upon a discharge of the last cartridge from the magazine, shoulder 64^a strikes against finger 107 of arm 106, shifting arm 106 forward and compressing 85 spring 111 until finger 108 is moved from 90 beneath arm 92. At this point, shoulder 64^a clears finger 107 and shoulder 64^b engages with arm 92, depressing the front end of lever 91. The moment shoulder 64^b has 95 fully depressed the forward end of lever 91, 90 pawls 65 and 67 swing clear of teeth 60^a and wheels 58 and 60 are urged back to normal position, withdrawing lug 64 from arm 92. The forward end of lever 91 is held depressed because the angular terminal end 100 102 of link 101 is past its dead center, thus spring 110 cannot push lever 91 up. The upward extension 92^b on arm 92 prevents finger 108 from catching over end of arm 92 and so making it impossible to close the 105 door 98. Door 98 may be snapped shut without shifting knob 109, and this will cause pawls 65 and 67 to be released by lever 91, shifting it to its normal position. Lever 110 110 will again be caught and held by finger 108 on arm 106 until it is again shifted forward either by hand or by the shoulder 64^a or lug 64. It will be noted that the unlocking of the wheel 58 by the release of pawl 67 will cause the follower to be carried down to 115 its original position. When the loading door is opened, eight cartridges may be loaded into the magazine. Only seven cartridges are actually carried in the magazine, the eighth cartridge being forced up into the 120 receiver. The gun is in condition at this time for continuing the firing. The spring 111 it will be seen acts to shift the upper end of the arm 106 rearward and thus to carry the arm 92 vertically. In this position the 125 forward end of the lever 91 will be locked from any accidental depression until the knob 109 is deliberately shifted by the oper-

ator or until the lug 64 contacts with the extension 92^b. When this occurs the curved under edge of the finger will act to shift the arm 106 forward against the force of the spring 111.

- 5 In case the gun misses fire, I provide means for manually retracting the breech block and breech bolt to their firing position and cocking the hammer. This manually 10 actuatable means consists of a rod 112 illustrated in Figs. 10 and 11 having its forward end bent to form a hook 113. The rear end of this rod passes through the rear end of the receiver and carries upon it a collar 114 15 through which a pin 115 loosely passes. One end of this pin is provided with a knob 116 while the other end is provided with a head 117. Between the collar 114 and the head 117 is disposed a spring 118 which forces the 20 pin downward in the collar 114 so that the knob 116 bears against the collar in the position shown in Figs. 2 and 11. This pin with its spring passes through openings 119 formed in a prolongation 120 of the rear end 25 of the receiver. The rod 112 is many sided and slides through an arm 121 to which a spring 122 is connected, this spring yieldingly resisting any rotative movement of the rod 112. The breech block is formed 30 with an opening 123 in which the forward end 113 of the rod 112 is adapted to engage. By this means a rotation of the rod 112 will initially cause a rotation of the breech block sufficient to release the lugs 21 from their 35 engagement with the lugs 22 and then a rearward movement of the rod 112 will draw the breech block rearward and cock the hammer. When the hammer has been cocked, the rod 112 is released therefrom permitting 40 the breech block to return to its initial position and permitting the gun to be again fired. Normally of course the spring 118 holds the pin 115 in the extension 120 of the receiver and in order to cock the piece it is 45 necessary to pull out this pin 115 against the force of the spring until it has cleared the extension 120, whereupon the rod 112 as before described may be rotated and retracted.
- 50 The general operation of my invention is as follows: When a cartridge explodes in the cartridge chamber, the recoil drives the breech bolt back, compressing the recoil spring 15. As the breech bolt is driven 55 back, the wide heavy threads on the breech bolt engage the similar threads on the inside of the forward part of the breech block 9. The pitch of these threads is relatively slow so that the force of the explosion will 60 be just strong enough to force the breech bolt back. As the breech bolt goes back, its threads cause the cylinder or breech block 9 to turn one-eighth turn to the left and this brings the lugs on the front end of the 65 breech block in line with the spaces between

the lugs 22 on the inside of the receiver. When these lugs on the breech block are clear of the projections 22, the whole breech block is free to move to the rear end of the receiver. As the breech block goes back it 70 compresses the two recoil springs 25, and when the breech block is about one inch from the rear of the receiver, it is stopped by the wings 23 arriving at the ends of the grooves 24. The two recoil springs then 75 immediately push the breech block back in its place in the front of the receiver unless this breech block is held from such movement by the locking bolt 94. When the breech block reaches its place at the front 80 end of the receiver the pressure of the two recoil springs 25 and of the inner recoil spring 15 forces the breech bolt forward relative to the breech block and as it goes forward the threads 13 turn the breech block 85 one-eighth turn to the right, thus again locking the breech block in its closed position. At the time that the breech block is moving toward the rear end of the receiver it accomplishes three things. It operates 90 the cartridge lifting mechanism as previously explained; operates the ejector, and it cocks the hammer. The cartridge lifting mechanism is actuated sufficiently to lift the top cartridge in the magazine in line with 95 the breech bolt and the chamber or barrel where it is held by the ejector lever 73 and by the inner magazine lid or gate 72 which is swung back by the cartridge as it is raised in line with the firing chamber. As 100 soon as the cartridge is started in the firing chamber and as the breech block is closing, the lid 72 will close under the action of spring 81. Upon a return of the breech block, it shoves the cartridge in the receiver 105 forward into the firing chamber and locks it in normal position and the cartridge is ready to be fired. The automatic action heretofore described is repeated each time that the trigger is pulled, discharging the piece until 110 the magazine is empty when the breech bolt is held open after the last shot is fired by means of the locking bolt 94 as previously explained. Just before the pawl 65 on the breech block engages with one of the teeth 115 60^a of the elevating wheel 60, the head 19 strikes against the ejector lever 76 swinging it toward the rear end of the receiver. This causes the operation of the ejector in the manner heretofore explained. As the ejector is placed slightly to the left of the middle of the top of the receiver, the stroke of the arm 74 of the ejector knocks the shell to the right side of the receiver and down and out through the ejecting passageway 7^a. The inner magazine lid 72 prevents the empty cartridge from falling into the magazine and also prevents the cartridges in the magazine from falling out when the rifle is 120 turned upside down. As long as the breech 125

65 130

block is at the rear end of the receiver, the ejector finger 74 is held down at right angles to the top of the receiver but as its lower end is a trifle to the right of the middle 5 plane of the receiver, there is room for the next cartridge from the magazine to come between it and the left wall of the receiver. In this way the cartridge is held firmly with help of inner lid 72 of the magazine 10 until it is pushed into the firing chamber by the breech bolt. The hammer 27 is cocked by the rearward movement of the breech block as heretofore explained. When the breech block moves toward the rear end 15 of the receiver, it shoves the hammer 27 back until the point on the front end of the hammer is shifted out of the path of movement of the breech block. It is then pushed back far enough so that the tooth 31 can be 20 engaged by the sear 41. As the trigger is likely to be held rearward at this time owing to the operator not having had time to release it, the front end of the sear 41 is depressed so that it cannot hold the hammer 25 but the rear end of the hammer sear is raised and catches behind the tooth 31 if the trigger has not been released. If this state of affairs occurs, then as soon as the trigger is released the rear end of the sear 30 is drawn down from in front of the tooth of the collar 30 and the hammer is pushed forward by the spring 28. As the front end of the sear 41 is elevated, however, it will engage the tooth 31. The result is the same, 35 therefore, whether the trigger be drawn back at the time that the hammer is cocked or whether the trigger has been released. As before explained, when the last cartridge in the rifle is fired, the elevating wheel is 40 released and the spring 49 acts to return the magazine follower to its initial position. The engagement of the lug 64 with the finger 92 lifts the rear end of the lid opening lever 91 and this movement of the lever 45 91 accomplishes four things at the same time. First it causes the lid of the magazine to open wide. The link 101 is curved so that with the help of the spring 101^a (see Fig. 7), the lower end of the link 101 50 will be thrown downward and then outside of the receiver when the lid is fully open so that the lid 98 has to be partly closed by hand before the spring 110 can push the forward end of the lever 91 up releasing the bolt 94 and the elevating wheel catch 67. Second, the upward movement of the bolt or rod 94 causes the locking of the breech block when the breech block is retracted, thus preventing the return of the breech 55 block to its normal position until the magazine lid is closed and the rod 94 depressed. Third, as the rod 94 is raised, the arm 96 catches under a projection extending from the left hand side of the breech bolt pawl 60 and lifts the breech bolt pawl clear of the

teeth 60^a on the elevating wheel 60. Fourth, the projection 95 releases the pawl 67 from its engagement with the teeth 60^a so as to leave the wheels 58 and 60 free to be turned backward to the original position by means 70 of spring 49.

It will be noted that this construction prevents the operator from snapping the hammer on an empty receiver and prevents losing any time by opening the magazine 75 breech bolt and lid by hand. The magazine lid being open and the magazine follower being in its lower position, the magazine is ready to be refilled with cartridges. When the magazine is filled, another cartridge 80 must be laid on top of the others and when the lid is closed it is pressed down between the other cartridges and the top cartridge in the magazine moves upward swinging the magazine lid 72 open and in line with breech bolt and firing chamber. If a cartridge 85 were not laid on top and pressed between the others and so push the top cartridge up in line with the firing chamber, the breech bolt would close behind an empty 90 chamber and it would be necessary to load the cartridge into the chamber by operating the rod 112 as previously explained. When the magazine door 98 is closed by hand, the bolt 94 is retracted, thus permitting the 95 breech block to return to its original position, whereupon the arm is again ready to be fired. When the lid 98 is closed and the lid engaging lever 91 is shifted to its normal 100 position, the lid opening latch formed by the members 106 and 108 catches the lever again and the lever cannot again be pushed down or the lid opened unless the lid opening catch above referred to is again pushed back either by the knob 109 or by the action 105 of the lug 64. If a cartridge misses fire, or if the breech bolt is closed on an empty chamber, or if for any reason it is necessary or desirable to open the breech block by hand, it may be opened by operating the rod 110 112 in a manner heretofore described. It will be noted that when the pin 115 is set in the perforations 119, the rod 112 will be so turned that the angular extremity 113 will be out of the way of the moving parts 115 of the breech block. The moment that the breech block commences to turn to the left to unlock as previously described, the automatic safety spring 84 commences to push the automatic safety plunger or rod 120 83 upward which causes the rod 87 to be pushed rearward into position beneath the trigger arm 45. If the trigger is held back at the moment that the breech block unlocks, the rod 87 can not get under the 125 trigger safety arm, but the moment the trigger is released the rod 83 is pushed upward by the spring 84 and the trigger is automatically locked against being pulled back. I thus provide two entirely separate safety 130

catches, one the bar 87 and allied parts being automatic in its action and the other the cam 90 which is manually operated.

The flexible connection 50 may be made of 5 any suitable material but preferably is made of chain. In order to indicate the number of cartridges in the magazine, the chain might be made of links of various colored metals. Thus some of the links may be 10 made of brass, some of iron and some of nickel so that the operator could tell how many cartridges were left in the magazine by looking through an opening 3^a in the bottom of the receiver. As long as, for instance, the brass links would be in view, he 15 would know that the magazine was full or nearly so, but when the nickel links came into view he would know that the magazine was nearly empty. Instead of having the 20 links of different colored metals, however, numbers corresponding with the number of cartridges in the magazine might be placed on the chain or flexible connection 50 at the proper positions, the first number being 8 25 when there are seven cartridges in the magazine and one in the chamber, and so on down to 1 indicating the last cartridge. These numbers could be seen through the opening 3^a. Preferably, however, the indicating numerals are placed upon the wheel 30 58 as previously stated.

In order to prevent small caliber cartridges from getting into the grooves or spaces between the lugs 22 and out of line 35 with the chamber and so being jammed against the barrel instead of going into the firing chamber when the breech block is closing, I may provide a rib in these grooves, such a rib being illustrated in Fig. 3 and 40 being designated 22^a, it being understood that the top lug 21 of the breech block is formed with a groove 21^a to accommodate this rib when the breech block is moving backward or forward.

45 It will be noted that the knurled knob of the hand safety device 90 is placed near the right hand edge of the under side of the receiver so that there will be no danger of accidentally pulling the trigger while operating this safety latch.

Having thus described my invention, what I claim is:

1. In a firearm, a vertically disposed 55 magazine, a vertically movable follower therein, a flexible connection engaging the follower, a rotatable member on which the flexible connection is wound, and means for rotatably shifting said member a predetermined distance upon each discharge of the firearm to thereby cause a discharge of cartridges from the magazine.

2. In a firearm, a vertically disposed 60 magazine, a vertically movable follower therein, a flexible connection extending for a portion of its length up the side of said

magazine, rotatable members upon which the opposite ends of the flexible connection are wound, means yieldingly resisting the upward movement of the flexible connection along the side of the magazine and constantly acting to retract the flexible connection, and means by which the flexible connection may be drawn upward along the side of the magazine a predetermined distance upon each discharge of the firearm to thereby cause an intermittent discharge of cartridges from the magazine.

3. In a firearm, a magazine, a movable follower therein, a flexible connection attached to said follower, means for winding up said flexible connection to cause the follower to travel through the magazine, and means actuated upon a discharge of the firearm for actuating said winding means.

4. In a firearm, a magazine, a follower disposed therein, a flexible connection operatively connected to the follower, means for winding up one end of said flexible connection to cause the follower to travel in one direction through the magazine, and means resiliently resisting said movement of the flexible connection.

5. In a firearm, a magazine, a follower disposed therein, a flexible connection operatively connected to the follower, means for winding up one end of said flexible connection to cause the follower to travel in one direction through the magazine, and resilient means for retracting the flexible connection after the last cartridge has been fired.

6. In a firearm, a magazine, a follower therein, a flexible connection connected to said follower, a coil spring operatively connected to one end of the flexible connection and acting to retract the latter and resist its movement in a feeding direction, a shiftable member operatively connected to the other end of the flexible connection and adapted to shift it in a feeding direction, and means actuated upon a discharge of the firearm for shifting said member a predetermined distance.

7. In a firearm, a magazine, a follower therein, a flexible connection operatively engaged with said follower, a retracting spring operatively connected to one end of the flexible connection and resisting its movement in one direction, a winding member operatively connected to the other end of the flexible connection, and means for rotating said winding member for a predetermined distance upon each discharge of the firearm.

8. In a firearm, a magazine having one wall thereof slotted, a follower, a flexible connection extending along said slotted wall and operatively connected through the slot to said follower, means for winding up said flexible connection to cause a retraction of the follower, and means automatically actu-

ated upon each discharge of the firearm for winding up said flexible connection to cause it to travel in a feeding direction.

9. In an automatic firearm, a magazine having a rear wall, a flexible connection traveling parallel to said rear wall, a follower in the magazine connected with said flexible connection and traveling therewith, a winding wheel over which said flexible connection passes, and means actuated upon each discharge of the firearm for rotating said winding wheel a predetermined distance.

10. In a firearm, a magazine having a rear wall and a bottom wall, a flexible connection traveling parallel to the bottom wall and to the rear wall, resilient means connected to the forward end of the flexible connection for retracting it, a winding wheel connected to the upper end of the flexible connection, a follower in the magazine operatively connected to the flexible connection to move therewith, and means actuated upon a discharge of the firearm for shifting said winding wheel a predetermined angular distance.

11. In a firearm, a magazine, a follower therein, a flexible connection passing beneath the magazine and then extending upward parallel to the rear wall thereof, a coil spring operatively connected to the forward end of said connection, a wheel disposed rearward of the magazine and to which the upper end of the said flexible connection is attached, and means actuated upon a discharge of the firearm for rotating said wheel a predetermined distance.

12. In a firearm, a magazine, means for elevating cartridges disposed in said magazine and including a flexible element, a rotatable member operatively connected to said flexible element and whereupon the flexible element may be wound, a member driven rearward by the explosion of a cartridge, and a pawl carried by said member and operatively engaging said rotatable member to shift it a predetermined angular distance upon each discharge of the firearm.

13. In a firearm, a magazine, a follower, a flexible element operatively connected to the follower, a winding wheel over which the flexible element passes, a toothed wheel operatively connected to the winding wheel, a member disposed in the breech of the firearm and rearwardly movable upon a discharge thereof, and a pawl depending from said member and adapted to engage the teeth of said wheel to shift the winding wheel through a predetermined angular distance upon each discharge of the firearm.

14. In a firearm, a barrel, a receiver, a magazine, a follower disposed in the magazine, a rotatable member mounted in the receiver, a flexible connection wound on said rotatable member and operatively connected to the follower to elevate the latter upon an

actuation of the rotatable member, a toothed wheel connected to said member, a breech block mounted in the receiver and rearwardly movable by the discharge of the cartridge, and a pawl carried upon said breech block and adapted to engage said wheel to thereby rotate the rotatable member through a predetermined distance upon each discharge of the firearm.

15. In a firearm, a receiver, a barrel, a breech block, a firing pin operatively mounted in the breech block, a spring actuated hammer, said hammer comprising a straight rod downwardly and rearwardly inclined and adapted when projected to engage said firing pin, a spring urging the hammer into a projected position, said firing pin having a head formed with a downwardly and forwardly beveled face, said head being engaged by the hammer in its projected position, said hammer being engaged by the beveled face of said head upon a rearward movement of the breech block and being thereby shifted out of the path of movement of said block, and trigger actuated means normally engaging the hammer upon its retraction.

16. In a firearm, a receiver, a barrel, a rotatable and rearwardly shiftable breech block in the receiver, a spring resisting the rearward movement of the breech block, a breech bolt mounted in the breech block for reciprocating movement but prevented from rotation, a spring resisting the rearward movement of the breech bolt, means for locking the breech block in the receiver against rearward movement, said means being unlocked by an initial rotation of the breech block, and coacting means on the breech bolt and block whereby an initial rearward movement of the breech bolt will cause a rotation of the breech block to an unlocking position to then permit the breech block to move rearward to open the breech.

17. In a firearm, a receiver, a barrel, a breech block mounted in the receiver for rotation and longitudinal movement, means yieldingly resisting the rearward movement of the breech block, a breech bolt mounted in the breech block for reciprocating movement, a spring normally projecting the breech bolt into the chamber beyond the breech block, means interlocking the breech block with the receiver when the breech is closed, means for preventing a rotary movement of the breech bolt but permitting its rearward movement independent of the breech block and against the force of said spring, and coacting means on the breech bolt and breech block whereby an initial rearward movement of the bolt will act to turn the breech block through a predetermined angular distance to thereby unlock the breech block and permit its rearward movement to open the breech.

18. In a firearm, a receiver; a barrel, a breech block mounted in the receiver and having radiating lugs, said receiver also having coacting radiating lugs adapted to interlock with the lugs of the breech block when the latter is in its closed position, a breech bolt mounted in the breech block, means normally projecting the breech bolt beyond the breech block, coacting screw threads formed upon the interior of the breech block and the extension of the breech bolt, and means permitting a rearward movement of the breech bolt but preventing a rotation thereof whereby to cause a rotational movement of the breech block through a predetermined angular distance upon an initial rearward movement of the breech bolt to thereby unlock the breech block and to cause a predetermined rotation of the breech block in the opposite direction upon a forward movement of the breech bolt.
19. In a firearm, a receiver, a barrel, said receiver having inwardly directed spaced lugs at its forward end, a hollow breech block mounted within the receiver and having outwardly projecting spaced lugs coacting with the lugs on the receiver to lock the breech block in its closed position but permitting rearward movement of the breech block after the breech block has been rotated a predetermined distance, a breech bolt mounted within the breech block and slideable therethrough, a spring holding said breech bolt projected, means on the breech bolt for permitting its rearward movement relative to the block but preventing rotation movement thereof, means yieldingly urging the breech bolt and block to their forward positions in the receiver, a firing pin disposed within the breech bolt, coacting means on the breech bolt and breech block for causing an unlocking rotation of the breech block upon initial rearward movement of the breech bolt to thereby permit the rearward movement of the breech block upon the explosion of a cartridge, a hammer, and a trigger for holding the hammer in a retracted position, said hammer being shifted to a retracted position upon the rearward movement of the breech block.
20. In a firearm, a receiver, a rearwardly movable breech block therein, a hammer, a trigger mechanism coacting with the hammer and including a trigger and trigger plate, and a trigger locking member shiftable into position between the trigger plate and trigger to prevent a rearward movement of the latter upon the initial rearward movement of the breech block.
21. In a firearm, a receiver, a breech block rearwardly movable therein, a hammer, a trigger co-operating with the hammer and including a forward extension, a trigger plate upon which the trigger is mounted, a

reciprocatable locking rod shiftable into engagement between the extension of the trigger and the trigger plate, and a spring-actuated vertically movable member operatively connected to said rod to shift it, said member being held from shifting movement in one direction by the presence of the breech block in its forward position.

22. In a firearm, a receiver, a rotatably movable breech block, a hammer, a trigger operatively connected thereto and having a forward extension, a trigger plate upon which the trigger is mounted, a vertically movable rod disposed in the forward end of the receiver, a spring urging said rod upward, a bell crank lever connected to the lower end of the rod, a locking rod connected to the other end of the bell crank lever and extending rearward to a point adjacent the extremity of said trigger extension, and means carried by said breech block for normally holding the first-named rod depressed when the breech block is in locked position but permitting the upward movement of said rod when the breech block is initially rotated to thereby cause the projection of the locking rod between the trigger extension and the trigger plate.

23. In a firearm, a receiver having a chamber, the forward wall of said chamber having a breech block opening, said wall being provided with inwardly radiating spaced lugs, a breech block rotatably mounted in said opening and having radiating spaced lugs coacting with the lugs on the wall of the receiver to prevent a rearward movement of the breech block until said breech block has been rotated a predetermined distance, means for causing a rotation of said breech block and the rearward movement of the breech block upon the explosion of a cartridge, a hammer, a trigger coacting therewith, a locking member shiftable into and out of position to lock the trigger from actuation, and a spring-actuated rod disposed in the forward end of the receiver and engaging with one of said radiating lugs on the breech block, said lug preventing an upward movement of the rod under the action of the spring, said member being operatively connected to said locking rod to cause a projection of the locking rod into engagement with the trigger upon a forward movement of the first-named rod when released by the rotation of the breech block.

24. In a firearm, a receiver, a barrel, a breech block mounted in the receiver for rearward movement upon the explosion of a cartridge, a breech bolt mounted in the breech block and normally projecting beyond the same but shiftable through the breech block, resilient cartridge engaging members mounted upon the forward extremity of the breech bolt, and ejecting devices

- actuated upon the rearward movement of the breech block to engage the empty shell and detach it from said gripping members.
25. In a firearm, a receiver having downwardly extending side walls, an intermediate partition in said receiver extending parallel to said side walls and defining on one side a magazine chamber and on the other side an ejecting chamber, a rearwardly movable breech block disposed in the receiver above said chambers, and a spring-actuated gate mounted upon said median wall and normally extending upward and laterally over the magazine chamber.
- 15 26. In a firearm, a receiver having downwardly extending side walls, an intermediate partition in said receiver extending parallel to said side walls and defining on one side a magazine chamber and on the other side an ejecting chamber, a rearwardly movable breech block disposed in the receiver above said chambers, a spring-actuated gate mounted upon said median wall and normally extending upward and laterally over the magazine chamber, and ejecting devices actuated by a rearward movement of the breech block to push the empty cartridge in the breech into the ejecting chamber.
- 25 30 27. In a firearm, a receiver having downwardly extending side walls and a median wall dividing the lower portion of the receiver into a magazine chamber and an ejecting chamber, the lower end of said ejecting chamber being open, and means actuated upon a discharge of the firearm for ejecting the empty cartridge into said ejecting chamber.
- 35 40 28. In a firearm, a receiver having a perforated rearward extension, a breech block movable rearward in said receiver upon the explosion of a cartridge, a rod shiftable into engagement with said breech block and longitudinally movable to retract the breech block, a pin movably mounted upon the rear end of said rod and forming a handle for the same, and means urging said pin through the perforation of the receiver to thereby lock it to the said receiver.
- 45 50 29. In a firearm, a receiver, a breech block normally locked from rearward movement but initially rotatable to unlock it from the receiver, said breech block being then movable rearward in said receiver, and means for manually retracting said breech block including a rotatable rod having a finger at its forward end adapted when the rod is rotated, to engage said breech block and rotate it to an unlocked position, said rod being rearwardly movable to retract the breech block after it is unlocked.
- 55 60 30. In a firearm, a receiver, a breech block therein rotatably and longitudinally movable in the receiver to open the breech, a longitudinally extending rod mounted in the receiver and having a bent finger at one end adapted, when the rod is rotated, to engage said breech block to initially rotate it to permit a rearward movement of the breech block and adapted to be retracted to retract the breech block, a collar mounted on the end of the rod, a pin passing through the collar, a spring urging said pin in one direction through said collar, and an extension on the receiver having perforations through which said pin normally passes to thereby lock the pin from rotation or longitudinal movement.
- 65 70 31. In a firearm, a spring-actuated hammer movable in a straight line, a trigger, a pivotally mounted sear having teeth at both ends, a member on the hammer adapted to be engaged by one or the other of the teeth, and an operative connection between the trigger and said sear.
- 75 80 32. In a firearm, a hammer, a trigger, and a hammer catch adapted to engage and hold the hammer in a retracted position whether the trigger is pushed forward or drawn to its rearmost position.
- 85 90 33. In a firearm, a hammer, a trigger, a sear pivoted at its middle and having retaining teeth at each end projecting toward the hammer, an operative connection between the trigger and the sear whereby to oscillate the latter upon a movement of the trigger in either direction, and a member on the hammer adapted to be engaged by one or the other of the teeth on the sear.
- 95 100 34. In a firearm, a receiver, a breech block mounted in the receiver and rearwardly movable therein upon the explosion of a cartridge, a downwardly and rearwardly extending straight hammer, a spring urging the forward end of the hammer against the rear end of the breech block, said hammer being movable to a cocked position by the rearward movement of the breech block, a pivoted trigger, a pivotally mounted sear having a tooth at each end and operatively connected to the trigger, and a member on the hammer adapted to be engaged by said tooth to thereby hold the hammer retracted.
- 105 110 35. In a firearm, a receiver, a magazine forming a part thereof, a follower in the magazine, a flexible connection connected to said follower, means for shifting said flexible connection in one direction to cause the elevation of the follower upon each explosion of a cartridge, and means for automatically causing a retraction of said flexible connection when the last cartridge in the magazine has been exploded.
- 115 120 36. In a firearm, a receiver, a magazine forming a part thereof, a flexible connection, spring-actuated winding means disposed at one end of said flexible connection, winding means disposed at the other end of said flexible connection and actuated to wind up said flexible connection thereon upon the ex- 130

losion of a cartridge, a follower in the magazine operatively connected to the flexible connection to move therewith, means for preventing an unwinding movement of the last-named winding means, and means actuated by the explosion of the last cartridge in the magazine for releasing said last-named means to permit the first-named means to retract the flexible connection and cause the follower to descend.

37. In a firearm, a receiver including a magazine having a door opening, a door to said magazine normally closing said opening, a follower in said magazine, means actuated upon each discharge of the firearm for causing an upward movement of the follower through a predetermined distance, and means actuated upon the discharge of the last cartridge in said magazine for opening the magazine door.

38. In a firearm, a receiver including a magazine having a door opening, a door normally closing said opening, a breech block in the receiver movable rearward upon the explosion of a cartridge, means actuated upon the explosion of a cartridge for feeding a new cartridge from the magazine into position before the breech block, and means actuated by the explosion of the last cartridge from the magazine, for opening said door and locking the breech block in a retracted position.

39. In a firearm, a receiver including a magazine, a follower in the magazine, a breech block in the receiver movable rearwardly therein upon the explosion of a cartridge, a flexible connection operatively connected to the follower, a spring winding means operatively connected to the forward end of the flexible connection, a winding wheel operatively connected to the rear end of the flexible connection and disposed rearward of the upper end of the magazine, means actuated upon a rearward movement of the breech block for rotating the winding wheel a predetermined distance to cause the ejection of a cartridge into the breech, locking means normally preventing unwinding movement of said winding wheel, and means actuated upon the explosion of the last cartridge from the magazine for releasing said locking means to permit the spring-actuated winding means to retract the flexible connection and the follower, said means simultaneously locking the breech block in a retracted position.

40. In a firearm, a receiver, a magazine, a breech block movable rearwardly upon the explosion of a cartridge, a follower in the magazine, means for causing a step by step upward movement of the follower upon the explosion of each cartridge and the corresponding rearward movement of the breech block, and means for returning the follower

to its initial position upon the explosion of the last cartridge from the magazine.

41. In a firearm, a receiver, a magazine, a breech block movable rearwardly upon the explosion of a cartridge, a follower in the magazine, means for causing a step by step upward movement of the follower upon the explosion of each cartridge and the corresponding rearward movement of the breech block, means for returning the follower to its initial position upon the explosion of the last cartridge from the magazine, a loading door to the magazine, and means for causing an opening movement of the loading door upon the firing of said last cartridge from the magazine.

42. In a firearm, a receiver, a magazine, a breech block movable rearwardly upon the explosion of the cartridge, a loading door to the magazine, and means for locking the breech block in a retracted position after the explosion of a cartridge until said door is closed.

43. In a firearm, a receiver, a magazine, a breech block movable rearwardly upon the explosion of the cartridge, means for feeding cartridges from the magazine upon each actuation of the firearm, a magazine door, means for causing the magazine door to automatically open upon the explosion of the last cartridge from the magazine, and means for locking the breech block in a retracted position caused by the discharge of said last cartridge and holding it in such locked position until the closing of the magazine door.

44. In a firearm, a receiver, a magazine, a breech block movable rearwardly upon the explosion of a cartridge, a follower in the magazine, means for causing a step by step upward movement of the follower upon the explosion of each cartridge and a corresponding rearward movement of the breech block, means for automatically returning the follower to its initial position upon the explosion of the last cartridge from the magazine, a loading door to the magazine, means for causing an opening movement of the loading door upon the firing of said last cartridge from the magazine and for simultaneously engaging the breech block to hold it in its retracted position until the loading door is closed.

45. In a firearm, a receiver, a magazine, a breech block movable rearwardly upon the explosion of a cartridge, a follower in the magazine, a winding wheel, a flexible connection engaging the follower and passing over said winding wheel, means on the breech block operatively engaging the winding wheel to rotate it a predetermined distance upon the rearward movement of the breech block, means resiliently resisting the upward movement of the flexible con-

nection, means for locking the winding wheel from reverse movement but permitting the winding movement thereof, and means actuated by the firing of the last 5 cartridge from the magazine for releasing the holding means engaging said winding wheel to thereby permit the return of the winding wheel to its original position and for automatically locking the breech block 10 in its retracted position.

46. In a firearm, a receiver, a magazine, a breech block movable rearwardly upon the explosion of a cartridge, a downwardly and rearwardly extending pawl on the 15 breech block, a follower in the magazine, a spring-actuated winding means disposed forward of the magazine, a flexible connection passing over the winding means and engaging said follower and extending up 20 the rear wall of the magazine, a winding wheel connected to the rear end of the flexible connection, means adapted to be engaged by said pawl for causing a predetermined movement of the winding wheel to 25 thereby wind up the flexible connection, a pawl holding said winding wheel from reverse movement under the force of the spring-actuated means, a magazine door, a vertically movable member adapted to 30 engage the breech block when the latter is retracted to hold it in retracted position, said member adapted to engage the holding pawl to release it from its engagement with the winding wheel and said member having 35 a prolongation adapted to engage the pawl on the breech block to hold it out of engagement with the winding wheel, and means actuated by the firing of the last 40 cartridge from the magazine for forcing said member upward to lock the breech block, unlock the winding wheel and shift said last-named pawl.

47. In a firearm, a receiver, a magazine, a door closing the lower portion of the 45 magazine, a rearwardly movable breech block, a wheel operatively engaged by said breech block upon its rearward movement to thereby rotate it a predetermined degree, a lever operatively connected to the door, and a 50 member mounted on the wheel and engaging said lever to rotate the door to an open position after the wheel has moved a predetermined degree.

48. In a firearm, a receiver, a magazine, 55 a door closing the lower portion of the magazine, a rearwardly movable breech block, a wheel operatively engaged by said breech block upon its rearward movement to thereby rotate it a predetermined degree, a lever, 60 a breech block locking device operatively connected to said lever and movable into engagement with the breech block when the latter is retracted and the lever is snifted, and means on the wheel for engaging said

lever to shift it after the said wheel has 65 moved a predetermined amount.

49. In a firearm, a receiver, a magazine, a door closing the lower portion of the magazine, a rearwardly movable breech block, a wheel operatively engaged by said breech 70 block upon its rearward movement to thereby rotate it a predetermined degree, a lever operatively connected to the door, a member mounted on the wheel and engaging said lever to rotate the door to an open position 75 after the wheel has moved a predetermined degree, and manually operated means for manually shifting said lever to open the door.

50. In a firearm, a receiver, a magazine, 80 a door closing the lower portion of the magazine, a rearwardly movable breech block, a wheel operatively engaged by said breech block upon its rearward movement to thereby rotate it a predetermined degree, a lever 85 operatively connected to the door, a member mounted on the wheel and engaging said lever to rotate the door to an open position after the wheel has moved a predetermined degree, and manually operated means for 90 locking the lever from movement or shifting the lever to open the door.

51. In a firearm, a vertically disposed magazine, a vertically movable follower therein, a flexible connection operatively engaged with said follower, said connection extending for a portion of its length parallel to the side wall of the magazine, means for giving said flexible connection a step by step movement to thereby elevate the follower step by step through the magazine, and means for indicating the degree to 95 which said flexible connection has been elevated to thereby indicate the number of cartridges in the magazine. 100

52. In a firearm, a vertically disposed magazine, a follower movable therein toward the upper end of the magazine, a flexible connection attached to said follower, a spring actuated winding drum over which 110 one end of the flexible connection passes, a winding wheel over which the other end of the flexible connection passes, means for shifting the winding wheel a predetermined distance upon the explosion of each cartridge to thereby unwind the flexible connection from the winding drum, and means co-acting with the winding wheel for indicating the position of the follower in the magazine. 115

53. In a firearm, a receiver, a magazine forming a part of the receiver, a follower therein, a flexible connection having a vertical stretch connected to said follower, a spring-actuated winding means connected 120 to the lower end of said connection, an automatically-actuated winding means connected 125 to the other end of said connection,

14 **1,126,726**
a breech block disposed in the receiver and through said side opening and indicating 10
movable rearward upon the explosion of a cartridge and adapted to operatively engage said winding wheel to rotate it a predetermined degree upon each rearward movement of the breech block, the receiver being provided with a side opening and the adjoining face of the winding wheel being provided with a series of numerals visible in presence of two witnesses.

FREDERICK A. DIESTELKAMP.

Witnesses: C. F. TEMPLE, M. L. STURGES.
